REFRIGERATION

Sven W. E. Andersson, Evansville, Ind., assignor
to Servel, Inc., New York, N. Y., a corporation
of Delaware

Application July 3, 1936, Serial No. 88,718

6 Claims. (Cl. 62—1)

My invention relates to refrigeration, and more particularly to a cooling element of refrigeration apparatus provided with means for indicating the formation of frost or ice thereon.

5 The invention, together with the objects and advantages thereof, will become apparent from the following description taken in conjunction with the accompanying drawing forming a part of this specification, and of which:

10 Fig. 1 is a sectional view of a refrigerator cabinet, taken on line 1—1 of Fig. 2, illustrating a cooling element embodying my invention for indicating the formation of frost thereon.

Fig. 2 is a sectional view taken on line 2—2 of 15 Fig. 1;

Fig. 3 is an enlarged fragmentary sectional view taken on line 3—3 of Fig. 1 when no frost or only a slight amount of frost has formed on the cooling element; and

20 Fig. 4 is a sectional view similar to that shown in Fig. 3 when a layer of frost of considerable thickness has formed on the cooling element.

Referring to Figs. 1 and 2, I have shown my invention in connection with a refrigerator cabinet 10 having thermally insulated walls 11 defining a storage compartment 12 into which access may be had by a door 13. Within the storage compartment 12 is arranged a cooling element 14 comprising a metal shell 15 adjacent to or about 25 which may be arranged an evaporator coil (not shown) of refrigeration apparatus for producing cold in a well-known manner.

The shell 15 is positioned in a corner of the storage compartment 12 and to the front and side 30 walls thereof are secured baffle plates 16 and 17, respectively, the baffle plates preferably being thermally insulated from the shell with the side baffle plate 17 being in fixed spaced relation from the shell to provide the space 18.

40 In order to determine when a layer of frost has accumulated on the shell 15 of the cooling element, I provide a hollow sleeve or tube 19 which extends alongside the shell in the space 18 and is secured to the front baffle plate 16 at an opening therein.

45 The tube 19 is preferably black and may be formed of a suitable composition material, such as hard rubber.

The side baffle plate 17 is provided with an inwardly extending flange or projection 20 adjacent the rear wall of the storage compartment 12, and the portion thereof which is in direct line with the hollow tube 19 is painted a suitable color, preferably black. Between the tube 19 and flange 20 the shell 15 is provided with an outwardly extending projecting part or lug 21. The

hollow tube 19 provides a direct line of vision with the flange 20, and renders the projecting part 21 invisible at all times when the space 18 is viewed through the opening in the front baffle plate 16.

When no frost or only a slight amount of frost has accumulated on the shell 15 and the space 18 is viewed through the tube 19, the black surface of the flange 20 is seen. When a predetermined layer of frost of considerable thickness has formed on the shell 15, as indicated by the dotted line 22, and the space 18 is viewed through the tube 19, a white surface is seen. This white surface is the frost that has accumulated on the projecting part 21 and which, as shown in Fig. 4, blocks off the view of the colored surface of the flange 20.

In view of the foregoing, it will be understood that the formation of frost on the cooling element, which is not directly visible and is concealed due to the baffle plates 16 and 17, can be readily noted. When the space 18 is viewed through the tube 19 and a white surface is seen, the operation of the refrigeration apparatus may be modified at will to instigate defrosting of the cooling element. If it is noted that a layer of frost of considerable thickness has accumulated on the shell 15 and at the same time it is desired to produce ice in the cooling element, the refrigeration apparatus may be permitted to operate in the usual manner to hasten the production of ice. After the production of ice, however, the fact that a white surface is visible through the tube 19 indicates the formation of frost on the cooling element whereby defrosting thereof may be manually instigated.

Although I have shown and described a particular embodiment of my invention, it will be apparent that various modifications and changes may be made without departing from the spirit and scope of my invention.

What is claimed is:

1. A refrigerator including a cooling element, and a member arranged to substantially conceal said cooling element, said member having an opening providing a line of vision sufficiently close to a part of said cooling element, so that a white surface is seen through said opening when a predetermined layer of frost has accumulated on said cooling element.

2. A refrigerator including a cooling element, structure for substantially concealing said cooling element, said structure having an opening providing a line of vision sufficiently close to a part of said cooling element, so that a white surface is seen through said opening when a predetermined layer of frost has accumulated on said cooling element.

terminated layer of frost has formed on said cooling element, and a member disposed between said structure and said part of the cooling element for rendering said part invisible through said opening when no frost or only a slight layer of frost has formed on said cooling element.

3. A refrigerator including a cooling element having a projecting part, a baffle plate mounted on the front of said cooling element and having an opening, and a member positioned alongside said cooling element between said baffle plate and said projecting part for rendering the latter invisible when the space behind said baffle plate is viewed through the opening, said projecting part being sufficiently close to the line of vision provided by said member whereby a white surface is seen through the opening when a layer of frost has accumulated on said cooling element.

4. A refrigerator including a cooling element having a projecting part, a baffle plate mounted on the front of said cooling element and having an opening, a member positioned alongside said cooling element between said baffle plate and said projecting part for rendering the latter invisible when the space behind said baffle plate is viewed through the opening, and a colored surface to the rear of said projecting part normally visible through the opening when no frost or only a slight amount of frost has accumulated on said cooling element, said projecting part being sufficiently close to the line of vision between the opening and said colored surface whereby a white surface is seen and the view of said colored sur-

face is blocked when a layer of frost has accumulated on said cooling element.

5. A refrigerator including a cooling element having a projecting part, a baffle plate mounted on the front of said cooling element and having an opening, a hollow member disposed alongside said cooling element, said member being secured to said baffle plate at the opening therein for rendering said projecting part invisible when the space behind said baffle plate is viewed through the opening, said projecting part being sufficiently close to the line of vision provided by said hollow member whereby a white surface is seen through the opening when a layer of frost has accumulated on said cooling element.

6. A refrigerator including a cooling element having a projecting part, a baffle plate mounted on the front of said cooling element and having an opening, a tubular member extending alongside said cooling element, said member being secured to said baffle plate at the opening therein for rendering said projecting part invisible when the space behind said baffle plate is viewed through the opening, and a colored surface to the rear of said projecting part normally visible through the opening when no frost or only a slight amount of frost has accumulated on said cooling element, said projecting part being sufficiently close to the line of vision provided by said tubular member whereby a white surface is seen on said projecting part and the view of said colored surface is blocked when a layer of frost has accumulated on said cooling element.
